UNITED STATES PATENT OFFICE.

EUGENE W. HAWLEY, OF MILWAUKEE, WISCONSIN.

CLOTHES-HANGER.

SPECIFICATION forming part of Letters Patent No. 787,622, dated April 18, 1905.

Application filed July 22, 1904. Serial No. 217,740.

To all whom it may concern:

Be it known that I, EUGENE W. HAWLEY, a citizen of the United States, and a resident of Milwaukee, in the county of Milwaukee and 5 State of Wisconsin, have invented certain new and useful Improvements in Clothes-Hangers; and I do hereby declare that the following is a full, clear, and exact description thereof.

My invention has especial reference to 10 clothes-hangers for use by occupants of sleeping-car berths; and it consists in certain peculiarities of construction and combination of parts whereby there is produced a convertible hanger adapted for use in either the lower or 15 upper berth, all as will be fully set forth hereinafter in connection with the accompanying drawings and subsequently claimed.

In the said drawings, Figure 1 is a view in elevation of my said device in position to be 20 attached to the curtains closing the lower berth, and Fig. 2 is a perspective view of said device folded together for storage or transportation.

Referring by numerals to the said drawings, 25 1 designates a strip of wire curved into a semicircular form and then doubled back on itself from each end, as indicated at 2 2, the extreme inner and adjacent ends of the parts 2 2 being bent into transverse loops or eyes 3 3, caught around the said part 1 adjacent to the center.

4 represents a horizontal stay-rod whose ends 5 5 are formed into loops or eyes caught around the lower and outer connecting ends 35 6 7 of the semicircular parts 1 2 2.

8 is a clamp-rod, one end of which is a loop 9, which is bent around the connecting end 7, while the other end of said rod 8 is an open loop or hook 10, adapted to engage with the 40 stay-rod 4 adjacent to the connecting end 6, and thus to clamp and secure in place a garment hung over the said stay-rod 4.

Swinging on the wire 1, just outside of the loops 3 3 of the parts 2 2, are the loops or eyes 45 11 11 of the ends of a wire bent first into an X shape and then extended outwardly to form

a double horizontal frame, to the upper part of which frame are rigidly secured (by fixed double clamps 12 12 and by solder, if needed) the safety-pins 13 13, whereby the device may 50 be secured to the curtains in front of a lower berth on a sleeping-car. Between the loops or eyes 3 3 of the ends of the wire 1 2 2 are the loops or eyes 14 14 on the ends of a wire which is doubled and bent to form the hook 15, 55 which when the user of the device has an upper berth is swung up over the curtain-rod, the frame having the safety-pins 13 13 being swung down out of the way, as shown in Fig. 2, where, in fact, the said hook 15 is also 60 swung down out of the way.

With this device, which when not in use is folded very compactly together, the traveler can in a moment either suspend the hanger with his (or her) garments therein from the 65 curtain-rod adjacent to the upper berth or pin the said hanger to the curtains if occupying the lower berth, and in either case thus have a convenient hanger for the discarded clothes instead of placing same in the usual 70 berth-net or back of the angularly-inclined end boards in the berth, which is not only inconvenient, but not adapted to hold clothing save in a crumpled wad, and when not in use the said device, as shown, may be folded into 75 small compass for the traveling-bag or suitcase.

Having thus described my invention, what I claim as new, and desire to secure by Letters Patent, is—

1. A clothes-hanger for sleeping-car berths, having a swinging frame with fastening devices for attachment to a curtain for the lower berth, and a swinging hook for engagement with the curtain-rod for the upper berth of 85 a sleeping-car, the said frame and said hook being attached so that either may be moved up into operative position for either berth, as desired, and so that both may be folded within the limits of the hanger proper, for storage or transportation.

2. In combination with a clothes-hanger

comprising a doubled-wire frame whose lower ends are connected by a stay-rod for holding the garments, a swinging and folding suspension-frame pivotally attached to the clothes-holding frame, and safety-pins rigidly secured to said suspension-frame.

5 In testimony that I claim the foregoing I

have hereunto set my hand, at Milwaukee, in the county of Milwaukee and State of Wisconsin, in the presence of two witnesses.

EUGENE W. HAWLEY.
